UNITED STATES PATENT OFFICE

WADE H. REICHARD, OF ROCHESTER, NEW YORK, ASSIGNOR TO GENERAL RAILWAY SIGNAL COMPANY, OF ROCHESTER, NEW YORK

SIGNALING SYSTEM FOR RAILROADS

Application filed July 23, 1929. Serial No. 380,346.

This invention relates to power interlocking systems for railroads, and more particularly pertains to features of cross-protection and the indication of the position of switch points in the well known dynamic indication type of electric interlocking system.

It has been proposed, as disclosed for example, in the application of William S. Henry, Serial No. 139,641, filed October 5, 1926, to provide a relay in the tower, sometimes called a "SS relay", which is controlled in accordance with the position and locked condition of the points of a track switch, and to utilize this SS relay as a means for checking the relay and circuits affording cross-protection.

One object of the present invention is to provide an improved means of this character for controlling the circuit of the switch repeating or SS relay, so that its energization is dependent upon the operation of the control lever and the flow of dynamic indication current.

A further object is to control the switch repeating or SS relay in accordance with the position and locked condition of the switch points, by alternating current superimposed upon the regular operating or control circuits for the switch machine, so as to avoid the need for extra wires between the switch and the tower for the operation of this SS relay, and also so as to afford an additional check of the correspondence between the position of the switch points and its control lever.

Various other objects of the invention, its characteristic features and advantages will be pointed out hereinafter as the description progresses. Other features or functions of the invention will be apparent to those skilled in the art.

The accompanying drawings illustrate in a diagrammatic and conventional manner certain specific embodiments of the invention applied to a single switch.

In describing the invention in detail, reference will be made to the accompanying drawings, in which like reference characters are used to designate like devices in the various figures, and in which,

Fig. 1 is a diagrammatic showing of one specific embodiment of the present invention; Fig. 2 is one modification of Fig. 1;

Fig. 3 is a second modification of Fig. 1.

Referring to Fig. 1 of the drawings, the points of the track switch TS are connected to and operated by a switch machine SM in the usual way, this switch machine SM being assumed to be of the type shown and described in the patent to W. K. Howe, No. 1,466,903, dated September 4, 1923. This switch machine SM comprises a direct current motor having an armature A and a field F, and also includes two groups of contacts automatically operated in accordance with the position and locked condition of the switch machine SM.

One of these groups of contacts, conveniently called pole changer contacts and designated PC, comprises four pairs of contact fingers or springs and two movable contact blocks 5 and 6. These contact blocks 5 and 6 are operated, in the manner shown and described in detail in the Howe patent above mentioned, by the gearing of the switch machine SM so as to be in one extreme position, as shown, when the switch machine is over and locked in that position, and to shift to the other extreme position, when the switch machine has operated and locked up in the other extreme position.

The other group of contacts, conveniently called point detector contacts and designated PD, are operated by the switch machine SM and additional connections to the switch points TS, in the manner as shown and described in detail, for example, in the patent to C. S. Bushnell, No. 1,507,236, dated November 25, 1924. These point detector contacts PD, comprise four pairs of contact fingers or springs and two movable contact blocks 7 and 8. When the switch points TS are in the normal position as shown, and are locked, the contact blocks 7 and 8 are in the normal position as shown. As soon as the switch machine is unlocked, and as long as it is operating, these contact blocks 7 and 8 are in the middle position, and do not engage with any of the pairs of contacts. When the switch points TS have been operated to the

100

reverse position and locked, the contact blocks 7 and 8 are shifted to the reverse position, opposite to that shown.

The point detector contacts PD are connected to the secondary of a local transformer 9, having a series resistance 10 in its secondary circuit, and also preferably a series resistance 11 in its primary circuit. This transformer 9 is supplied with alternating current from a pair of wires, connected to a suitable alternating current source, and extending between the tower and the switch.

In the interlocking tower, there is the usual manually operable control lever L, having contact members 12 and 13 engaging pairs of contact springs in the normal and reverse position of this lever. This lever L is preferably provided with an electric lock (not shown), but does not have the usual indication mechanism and indication magnet.

Associated with the lever L is an electro-responsive device IR, preferably of the construction of the indication selector as shown and described for example in the patent to W. K. Howe, 1,550,611, dated August 18, 1925, and comprises two coils 56 and 74 acting, when alternately energized, to shift a movable contact 29 back and forth to close circuits through the stationary contact 30 and the two contacts 28 and 87.

Also associated with the lever L is a cross-protection relay P of the usual construction, such as shown and described for example in the patent to W. S. Henry, 1,334,900, dated March 23, 1920, or as shown in my prior Patent 1,713,494, dated May 14, 1929. This cross-protection relay P, as diagrammatically illustrated comprises a coil or winding adapted, when energized with current of one polarity, to attract an armature for releasing a spring actuated contact 66 to open the circuit through its cooperating contacts, indicated conventionally as arrows.

The power supply for operating the switch machine SM, being controlled by the lever L, is furnished by a battery 14, or other suitable direct current source. To prevent maintaining severe overload currents in case of shunts or the like, suitable overload devices may be employed, which in this specific case has been shown as a fuse J.

The switch repeater or SS relay, designated WP, is located in the tower and is preferably a three-position relay of the two-element or polyphase alternating current type. This relay WP has one of its windings, conveniently termed a local winding 3, connected to a transformer 15 energized from the alternating current line circuit. The other or line-phase winding 4 is connected to the common return wire C for the switch machine SM and to a contact 30 of the indication responsive device IR. If both windings of the relay WP are energized with alternating current, suitably displaced in time phase, a con-

tact finger 16, or armature, of this relay WP is operated to one extreme position, as shown; and, if the relative instantaneous polarity of the alternating current energizing one of these two windings is reversed, this contact finger 16 is operated to the other extreme or dotted line position. If no alternating current flows through the line-phase winding, the contact finger 16 assumes its intermediate or neutral position.

The switch repeater relay WP may be used for various purposes, familiar to those skilled in the art, such as governing the indications of the signals of the route over the switch governing the relay WP, for indication purposes, or the like. No particular arrangement of circuits governed by the relay WP has been shown, but it may be assumed that the contact finger 16 of this relay WP in its normal and reverse positions controls the indications of the signals governing traffic over the switch TS.

Operation.—The operation of the switch machine SM is controlled by the movement of the lever L in the usual way. It is contemplated that the operation of the switch machine SM would be safeguarded by a lever lock, route locking, detector track circuit control, and the like, in accordance with established practice; but it is unnecessary to explain these features, which are familiar to those skilled in the art.

The parts and circuits, as shown in Fig. 1 of the drawings, are in the normal conditions existing when the lever L is in the normal position, and the switch machine SM and switch points TS are in the normal position and locked. With the parts in this normal condition, the line-phase winding of the relay WP is energized by the local transformer 9 at the switch, over a circuit including the reverse operating wire R and the common return wire C, which circuit is traced as follows:—from the right hand terminal of the secondary of transformer 9, through the series resistance 10, wire 20, fixed contact 21, movable contact block 7, fixed contact 22, wire 23, reverse operating wire R, fixed contact 24, movable contact 13, fixed contact 25, wire 26 and 27, fixed contact 28, movable contact 29, fixed contact 30, wire 31, line-phase winding 4 of relay WP, wires 32 and 33, winding of polarized relay P, wire 34, common wire C, wires 35 and 36, fixed contact 37, movable contact block 8, fixed contact 38, wire 39, through the left hand terminal of the secondary of the transformer 9.

Although the armature A and the field winding F of the switch machine motor are connected across the secondary of the transformer 9 over wire 20, fixed contact 21, movable contact block 7, fixed contact 22, wires 23 and 45, fixed contact 46, movable contact block 6, fixed contact 47, wires 48 and 49, armature A, wire 50, fixed contact 51, movable

contact block 5, fixed contact 52, wires 53 and 54, field winding F, wires 55, 35 and 36, fixed contact 37, movable contact block 8, fixed contact 38, wire 39, the armature A and the field 5 F of this motor are of high impedance to alternating current, so that sufficient voltage drop is maintained across the circuit supplying alternating current to the line phase winding 4 of the relay WP.

10 Also, although the normal coil 56 of the indication responsive device IR is connected in multiple with the line-phase winding 4 of the relay WP over wires 32, 44 and 57, coil 56 of indication responsive device IR, wires 15 58 and 27, fixed contact 28, movable contact 29, fixed contact 30, and wire 31, this coil 56 has such a high impedance to alternating current, that a sufficient voltage drop is maintained for supplying operating current to 20 said line-phase winding 4 of relay WP.

Thus, with the switch TS and its control lever L in the normal position, the switch repeater relay WP is energized, as shown, so as to establish through the normal contacts of the relay WP such signal control circuits, or the like, as may be found expedient to obtain the desired protection.

If the switch points TS are unlocked or shifted from the normal position, for any 25 reason, due to hand operation, or a cross or ground, the point detector contacts PD open the circuit above traced for energizing the line-phase winding 4 of the relay WP, and the contact finger 16 of this relay WP assumes its neutral or deenergized position, putting to stop the signals governing the traffic over the switch TS in question, or otherwise safeguarding train movement over such a switch which is not locked, or out of 30 correspondence with its control lever L.

If the switch machine SM should be cranked by hand, or otherwise caused to assume its reversed locked position, and even though the point detector contacts PD are 35 closed in the reverse position, the line-phase winding 4 of the relay WP is not energized, because the switch machine SM and switch points TS are out of correspondence with the position of the control lever L. This is 40 because the reverse energizing circuit for the relay WP, including the point detector contacts PD closed in the reverse position, is over the normal operating wire N, through the reverse lever contacts 77 and 78, and the reverse contacts 30 and 87 of the indication responsive device IR, both of these contacts being opened with the lever L in the normal position.

When the lever L is manually shifted from 45 the normal position to the reverse position, a reverse operating circuit is established as follows:—from the positive terminal of battery 14 through wire 59, fuse J, wires 60 and 61, fixed contact 62, movable contact 12, fixed contact 63, wire 64, reverse operating wire

R, wire 45, fixed contact 46, movable contact block 6, fixed contact 47, wires 48 and 49, armature A, wire 50, fixed contact 51, movable contact block 5, fixed contact 52, wires 53 and 54, field winding F, wire 55, common wire C, wire 65, contact 66, wire 67 to the opposite terminal of battery 14.

As soon as the lever L is moved from the normal position, the normal energizing circuit for the line-phase winding 4 of the relay WP is broken at the normal lever contacts 24 and 25, so that the relay WP is at once deenergized, putting the signals to stop, or the like. As soon as the switch machine SM is unlocked, the point detector contacts PD are shifted to the intermediate or open circuit position, making another break in the normal energized circuit for the line-phase winding 4 of the relay WP, so that this relay WP remains deenergized even though the lever L should be returned to its normal position. Thus, as soon as the switch machine SM is operated from its normal locked position, the relay WP is deenergized.

After the switch machine SM completes its operation to the reverse position, due to direct current power being supplied to its reverse operating circuit, the movable contact blocks 5 and 6 of the pole changer contacts PC are automatically shifted to the extreme reverse position, establishing a dynamic indication circuit as follows:—from the upper terminal of the armature A, through wire 49, fixed contact 70, movable contact block 5, fixed contact 71, wires 72 and 54, field winding F, wire 55, common wire C, wire 34, winding of cross protection relay P, wires 33, 44 and 73, reverse operating coil 74 of indication responsive device IR, wires 75 and 76, fixed contact 77, movable contact 13, fixed contact 78, wire 79, normal operating wire N, fixed contact 80, movable contact block 6, fixed contact 81, wires 82 and 50, to the opposite terminal of the armature A.

The dynamic indication current, flowing for a short interval after the switch machine SM has completed its operation, energizes the reverse coil 74 of the indication responsive device IR, shifting its contact 29 from the normal position shown to the reverse dotted line position, thereby establishing a reverse energizing circuit for the line-phase winding of the relay WP, which circuit may be traced as follows, bearing in mind that the lever L is now in the reverse position and the point detector contacts PD are closed in the reverse position:—from the right hand terminal of the secondary of transformer 9, through series resistance 10, wires 20 and 83, fixed contact 84, movable contact 8, fixed contact 85, wires 86 and 35, common wire C, wire 34, winding of polarized relay P, wires 33 and 32, line phase winding 4 of relay WP, wire 31, fixed contact 30, movable contact 29,

fixed contact 87, wires 88 and 76; fixed contact 77, movable contact 13; fixed contact 78, wire 79, normal operating wire N, wire 89; fixed contact 90, movable contact block 7, fixed contact 91, wires 92 and 39, to the opposite terminal of the secondary of transformer 9.

The operation of the switch from the reverse to the normal position is similar to that described involving similar circuits, and need not be described in detail.

Thus, if the switch machine SM has operated properly to move the switch points, has locked up, and has transmitted a dynamic indication current through the cross-protection relay P, the relay WP is again energized, but with such instantaneous relative polarities in the local and line-phase windings, that the contact 16 assumes the reverse position. It will be evident that, before the relay WP can thus be energized to the reverse position, the indication responsive device IR must have operated its contact to the reverse position, and this in turn occurs only if the cross-protection circuit through the cross-protection relay P is intact to permit the flow of dynamic indication current through the reverse operating coil 74 of said indication responsive device IR.

In this way, the integrity of the cross-protection circuit is checked at the end of each authorized or normal operation, and it is assured that the cross-protection relay P and its circuit connections, protecting the switch machine SM against improper operation by crosses, is in condition to function before the relay WP is energized to permit the clearing of signals governing traffic over the switch TS.

In this connection, it should be understood that an SS relay, controlled in the usual manner over a separate polarized circuit, assures that the switch is over and locked in the proper position, before the signal can be cleared. Such an SS relay will also act to put the signals to stop, if the switch is improperly operated by cross or otherwise, from its existing position out of correspondence with its control lever. Such an SS relay, however, does not prevent operation of the switch machine by a cross or the like, after a train has accepted the signal, and while the train is passing over the switch. Such protection is afforded by this invention, because in addition to the continuing indication of switch position by the relay WP, the cross-protection relay P and its circuit connections, which are checked upon each operation, prevent such an improper operation of the switch machine by cross, in the well known manner. For example, if a cross should occur between the control wires N and R, the current tending to operate the switch machine would have a path through the cross protection relay P in a direction to open its contacts 66

and break the common return connection from the switch machine motor.

It should be noted that the energization of the relay WP to move its contact finger 16 to a new position is dependent not only upon the point detector contacts PD, operated in accordance with the position of the switch points TS and their locked condition, but also upon the dynamic indication current, so that the operation of the relay WP to a new position shows that the switch points TS have been operated over and locked up by power in the usual authorized way, rather than merely that the switch points TS are over and locked in a certain position. This affords a desirable additional check upon the proper and normal operation of the system. For example, if the operator should move the lever L to the reverse position, and the switch machine SM for some reason should fail to respond, and then was operated by hand to the reverse position, the relay WP would not be energized, since there had been no dynamic indication current transmitted through the reverse coil 74 of the indication responsive device IR to move its contact 29 into a position corresponding with the lever contacts and complete the reverse energizing circuit for the relay WP. Thus, even through the lever L and switch machine SM would be in corresponding positions under the conditions assumed, the fact that this condition was brought about by an abnormal operation, would be indicated by the relay WP.

The resistance 10 in series with the secondary of the transformer 9 is employed, because, when operating current is first supplied to the switch machine SM, and before the point detector contacts PD assume the neutral or open position, current tends to flow through the secondary of the transformer, and if a sufficient value of direct current flows in the secondary, the core of this transformer 9 becomes magnetized above saturation, which destroys the reactance of the primary to a degree that might injure it or blow fuses in the primary circuit. Also, without this series resistance 10, the secondary of the transformer 9 would act to shunt the operating current from the motor at the beginning of the operation and prior to the shifting of the point detector contacts PD. This series resistance 10 is also desirable because the secondary of the transformer 9 is in multiple with the next operating coil of the indication responsive device IR, across the armature A and field F of the motor, so that, if this resistance were not used, the low ohmic resistance of the secondary of this transformer 9 would interfere with the proper energization of the coils 56 and 74 by the dynamic indication current. If desired, a condenser may be used in lieu of this series resistance 10. A resistance 11 is preferably used in series

with the primary of the transformer 9, so as to obtain more economically the desired voltage regulation and operating characteristics of this transformer 9 over the varying line 5 wire resistances, due to the varying distances between the switches and tower.

Fig. 2 shows a modification in which additional normal and reverse coils 100 and 101 respectively, are employed for the indication 10 responsive device IR, these coils 100 and 101 being included in the connections, as shown, between the battery 14 and the lever contacts 38 and 62 through which normal and reverse operating current is supplied respectively. 15 With the parts in the normal position, as shown in Figs. 1 and 2, both of these additional coils 100 and 101 are deenergized, the circuit through the reverse coil 101 being broken at the lever contacts 62 and 63 and 20 the circuit through the normal coil 100 being broken at the contacts 80 and 81 of the pole changer PC.

When the lever L is shifted to the reverse position, the operating current in the reverse 25 operating circuit flows through the additional coil 101 and holds the contact 29 of the indication responsive device IR in its normal position, so that any stray current applied to the normal operating wire N, due to a cross 30 or the like, even though such stray current may flow through the reverse operating coil 74, will not operate the contact 29 while motor operating current is flowing.

Also, if the operator, after having moved 35 the lever L to the reverse position, should return it to the normal position, the flow of current in the normal operating circuit, established due to the reversable characteristics 40 of the switch machine SM, as more fully explained in the Howe Patent 1,466,903, above mentioned, would flow through the additional coil 100 and operate the contact 29 to a reverse position, breaking the normal energizing circuit for the relay WP, and preventing 45 its energization until the dynamic indication current for operation of the indication responsive device IR, energizes the coil 56 of the device IR and restores the contact 29 to the normal position. In this way, the integrity of the cross-protection circuit is 50 checked after a partial operation of the switch machine SM, as well as after each complete normal operation. In other words, if the switch machine SM should be partially 55 operated in one direction, and then reversed in midstroke, in accordance with the modification in Fig. 2, the dynamic indication current would have to flow again before the relay WP would be energized, thereby checking 60 the cross-protection circuit after such a partial operation of the switch machine SM, as well as at the end of a complete operation, as in Fig. 1.

While it is desirable, in order to economize 65 in the amount of wire between the tower and

the switch machine, to control the switch repeater relay WP over the same wires used for operating the switch machine, as shown in Fig. 1, this relay WP may be operated over a separate line circuit, in such a modified arrangement as shown in Fig. 3. Referring to Fig. 3, the point detector contacts PD are connected to the transformer 9, in the same way as in Fig. 1, but without the limiting resistance 10; and these point detector contacts are connected to separate line wires 93 and 94, running from the switch machine SM to the tower, and connected respectively to the line-phase winding 4 of the relay WP, through two extra pairs of lever contacts 95-96 and 97-98 included in the normal and reverse positions of the lever. The contacts 28 and 87 of the indication responsive device IR are connected by wires 102 and 103 to the lever contacts 96 and 98. 70 75 80 85 90

This modification of Fig. 3 operates in the same manner as above explained in connection with the embodiment of Fig. 1, with the energizing circuits for the relay WP in Fig. 3 being readily traced by analogy to those of Fig. 1. 95

From the foregoing it can be seen that there is provided by this invention a switch repeater or SS relay, which not only affords a continuous indication of the position and locked condition of the track switch points, but also serves to check the integrity of the cross-protection circuit after each operation, said SS relay also assuming a new operated position, only if the switch machine and lever are in correspondence as the result of a normal or authorized power operation. The invention also provides for the control of this SS relay over the regular switch machine operating circuits, although it should be understood that this SS relay may be controlled in other ways, and over a separate pair of wires as shown in Fig. 3, without departing from the features of the invention characteristic of the use of the indication responsive device IR, in combination with lever contacts. 100 105 110

While certain specific embodiments of the invention have been shown and described, it should be understood that these particular constructions and arrangements of parts and circuit are susceptible to considerable modification and adaptation in practice, without departing from the invention, its characteristic features, and advantages. 115

Having described my invention, I now claim:—

1. In an interlocking system for railroads, a track switch, a switch machine for operating said switch, a control lever, two control wires and a common return wire connecting said lever and said switch machine, an electro-responsive means operable to different positions to indicate the position of the switch points of said switch and having normal and 120 125 130

- reverse energizing circuits, each respectively including one of said control wires, a distinctive source of current and said common return wire.
5. 2. In an interlocking system for railroads, a track switch, a switch machine for operating said switch, a control lever, two control wires and a common return wire between said switch and said lever providing normal and reverse operating circuits for said switch machine, and means for indicating the condition of said switch machine operable by alternating current flowing in normal and reverse energizing circuits respectively, including said operating circuits of the switch machine.
10. 3. In an interlocking system for railroads, a track switch, a switch machine for operating said switch, a control lever, two control wires and a common return wire between said switch and said lever providing normal and reverse operating circuits for said switch machine, a three position relay in the tower responsive only to current distinctive from the current for operating said switch machine and having normal and reverse energizing circuits each including respectively one of said control wires and said common return wire.
15. 4. In an interlocking system for railroads, a track switch, a switch machine for operating said switch, a control lever, two control wires and a common return wire between said switch and said lever providing normal and reverse operating circuits for said switch machine, a relay in the tower, normal and reverse energizing circuits for said relay including respectively, one of said control wires and said common return wire, and contacts associated with said switch for supplying alternating current to said energizing circuits of opposite instantaneous polarity when switch points are over and locked in their extreme positions.
20. 5. In an interlocking system for railroads, an electrically operated switch machine, a control lever having normal and reverse contacts, a relay in the tower having normal and reverse energizing circuits including said lever contacts, and means responsive to indication current generated dynamically by said switch machine after operation thereof for controlling said energizing circuit for said relay.
25. 6. In an interlocking system for railroads, an electrically operated switch machine, a control lever having normal and reverse contacts, a relay in the tower having normal and reverse energizing circuits, an indication responsive device energized by indicaton current generated dynamically by said switch machine after each operation thereof for closing normal and reverse contacts respectively included in the energizing circuits for said relay, and means operated by said lever for opening and closing the energizing circuits for said relay.
7. In an interlocking system for railroads, an electrically operated switch machine, a control lever having normal and reverse contacts, a three position relay in the tower having normal and reverse energizing circuits respectively including said normal and reverse lever contacts, and means operated by dynamic indication current produced by said switch machine for alternately closing said circuits.
75. 8. In an interlocking system for railroads, a control lever, a distant switch machine having normal and reverse operating wires governed by said control lever, a contact means controlled by dynamic indication current received over said normal and reverse operating wires alternately, a three position relay, and means operable to control said three-position relay in accordance with said distant switch including said contact means.
80. 9. In an interlocking system for railroads, a control lever in an interlocking tower, a distant switch machine, two control wires and a common return wire connecting said control lever with said switch machine, a relay in said interlocking tower responsive only to current distinctive from the current capable of operating said switch machine and operable to either of three positions, and means, including one of said two control wires with said common return wire, operable to control said relay to one of its three positions, and means, including the other of said two control wires with said common return wire, operable to control said relay to another of its three positions.
85. 10. In an interlocking system for railroads, a control lever, a distant switch machine having normal and reverse operating wires governed by said control lever, a dead beat armature controlled by dynamic indication current received over said normal and reverse operating wires alternately, a three-position relay, and means operable to control said three-position relay in accordance with said distant switch machine including said normal and reverse operating wires alternately used, and contacts operably controlled by said dead beat armature.
90. 11. In an interlocking system for railroads, a control lever, a distant switch machine having normal and reverse operating wires, governed by said control lever, two electro-magnetic coils, a dead beat armature being controlled to one of two extreme positions by energization of either one of said electro-magnetic coils, means operably controlling energization of said electro-magnetic coils by dynamic current supplied from said distant switch machine over said normal and reverse operating wires alternately, a relay capable of assuming any one of three positions, and means operable to control said

relay to a particular position including, said normal and reverse operating wires alternately used, and contacts operably controlled by said dead beat armature.

5 12. In an interlocking system for railroads, a control lever, a distant track switch controlled by a switch machine, two operating wires connecting said control lever with said distant switch machine, an electro responsive means indicating the position of said track switch, and means operably controlling said electro-responsive means including said two operating wires alternately used, contacts operated by said control lever, 10 and contacts operably controlled by dynamic current received from said distant switch machine.

13. In an interlocking system for railroads, a control lever, a distant track switch controlled by a switch machine, two operating wires connecting said control lever with said distant switch machine, an alternating current relay capable of assuming any one of three positions and indicating the positions assumed by said distant track switch, and means operably controlling said alternating current relay including, said two operating wires alternately used, contacts operated by said control lever, and contacts operably controlled by dynamic current received from said switch machine.

14. In an interlocking system, the combination with a distant track switch, a distant operating switch machine, a control lever for said switch machine, and an indication selector having coils included in the dynamic indication circuit of said switch machine, of an alternating current relay, contacts governed by the condition of said indication selector, and means operably controlling said alternating current relay, with said means including, contacts controlled by said control lever, and said contacts governed by the condition of said indication selector.

15. In an electric interlocking system, the combination of a switch machine, a normal and a reverse control circuit for said switch machine, a normal and a reverse indication circuit for said switch machine, an indication responsive device, a three-position alternating current relay, means operably controlling said indication responsive device over said normal or reverse indication circuit, and means operably controlling said three-position alternating current relay over said normal or reverse indication circuit after said indication responsive device has been operably controlled in response to a completed operation of said switch machine.

16. In an interlocking system for railroads, a control lever, a distant track switch controlled by a switch machine, two control wires connecting said control lever with said distant switch machine, an alternating current relay capable of assuming either of two ex-

treme positions in correspondence with said distant track switch in one of two extreme positions, and capable of assuming a deenergized position upon movement of said distant track switch from an extreme position, and means operably causing said alternating current relay to assume a position in correspondence with said distant track switch, including, contacts jointly operated by said distant track switch and said switch machine, said two control wires alternately used, contacts operated by said control lever manually controlled, contacts operably controlled by dynamic indication direct current received over said two control wires alternately used.

17. In an interlocking system for railroads, a track switch, a switch machine controlling said track switch and being operated over normal and reverse operating wires in conjunction with a common return wire, a transformer local to the track switch, a series resistance in the primary circuit of said transformer, a series resistance in the secondary circuit of said transformer, and point detector contacts jointly operated by said track switch and said switch machine for alternately connecting said secondary circuit of said transformer to said normal or reverse operating wires and said common return wire, having opposite instantaneous polarities when said switch is over and locked in extreme positions.

18. In an interlocking system for railroads of the dynamic indication type as shown and described, a track switch controlled by a switch machine, a control lever having normal and reverse contacts, and electro-responsive means in the tower indicating the position of said track switch and having normal and reverse circuits including said normal and reverse contacts respectively, and normal or reverse contacts respectively operably controlled by direct current dynamic indication current from said switch machine.

19. In an interlocking system, a distant switch machine, a normal and a reverse control circuit for said switch machine, a normal and a reverse indication circuit from said switch machine, an indication responsive device having normal and reverse coils included respectively in said normal and reverse indication circuits and having normal and reverse coils included respectively in said normal and reverse control circuits, an electro-responsive device indicating the position of said switch machine, and means operably controlling said electro-responsive device for a given indication condition including, said normal or reverse indication circuit, and contacts operably controlled by said indication responsive device.

20. In an interlocking system for railroads, a track switch, a switch machine for operating said switch, a control lever, two

control wires and a common return wire connecting said lever and said switch machine, an electro responsive means operable to different positions to indicate the position of the switch points of said switch and having normal and reverse energizing circuits, each respectively including one of said control wires and said common return wire, and each established only if said lever and said switch machine assume corresponding positions.

current generated by said switch machine after said lever and switch machine assumes corresponding positions.

In testimony whereof I affix my signature.

70

WADE H. REICHARD.

75

21. In an interlocking system for railroads, a track switch, a switch machine for operating said switch, a control lever, two control wires and a common return wire between said switch and said lever providing normal and reverse operating circuits for said switch machine, and means for indicating the condition of said switch machine operable by alternating current flowing in normal and reverse indicating circuits respectively, one of said indicating circuits including one control wire and said common wire and the other indicating circuit including the other control wire and said common wire.

22. In an interlocking system for railroads, a track switch, a switch machine for operating said switch, a control lever, a three position relay in the tower having normal and reverse energizing circuits each including respectively one of said control wires and said common return wire and contacts closed only when said lever and switch assumed corresponding positions.

23. In an interlocking system for railroads, a control lever, a distant switch machine having normal and reverse operating wires, a dead beat armature controlled by dynamic indication current received over said normal and reverse operating wires alternately, a three-position relay, and means operable to control said three-position relay in accordance with said distant switch machine including said normal and reverse operating wires alternately used, and also including contacts operably controlled by said dead beat armature.

24. In an interlocking system for railroads, the combination with a distant track switch, of a switch machine for controlling said track switch; a lever; a normal wire, a reverse wire and a common wire connecting said lever and switch machine; a normal circuit for operating said switch machine including said normal wire and said common wire; a reverse circuit for operating said switch machine including said reverse wire and said common wire; indicating means at said lever controlled over two distinctive circuits each circuit including a contact of said lever, a contact operated in accordance with the switch points of said track switch and a contact closed only in response to dynamic
